UNITED STATES PATENT OFFICE.

ISIDOR SCHULZ, OF NEW YORK, N. Y.

DESIGN FOR A GAME-BOARD.

SPECIFICATION forming part of Design No. 25,311, dated March 31, 1896.

Application filed April 4, 1895. Serial No. 544,487. Term of patent 3½ years.

To all whom it may concern:

Be it known that I, ISIDOR SCHULZ, a citizen of the United States, residing in the city, county, and State of New York, have invented 5 and produced a new and original Design for a Game-Board, of which the following is a specification, reference being had to the accompanying drawings, forming part thereof.

In the accompanying drawings, Figure 1 is 10 a plan view of a game-board, showing my design; and Fig. 2 is an edge view of the design.

The leading features of my design consist in a plate or board 2, having a border or rim 3 and a central raised piece 4, the latter being entirely within the border or rim and separated equal distances therefrom at its sides and ends. The central raised piece 4 is oblong in general form; but the contour thereof is modified by having the four corners thereof 15 cut away diagonally, as shown at 5, the diagonal lines of the corners being practically of the same length. On or at each side of the center piece are also formed two rectangular oblong notches or recesses 6, which divide the center piece into three divisions of substantially equal lengths, and the said notches or recesses extend an equal distance into the center piece from the opposite sides, said dis-

tance being about two-fifths of the width of said center piece. At each end of the center piece is also a notch or recess 7 arranged centrally of the ends and being practically of the same form, depth, and width as the side notches or recesses 6, and, as will be seen, by cutting away the corners of the raised central piece, as hereinbefore described, about two-thirds of the end lines of said piece are removed and about half of the side lines, and, as will also be seen, the sides and ends of the central raised piece are practically at equal 35 distances from the sides and ends of the plate or body piece 2 and the border or rim surrounding the same.

Having fully described my design, I claim and desire to secure by Letters Patent— 45

The design for a game-board herein shown and described.

In testimony that I claim the foregoing as my invention I have signed my name, in presence of two witnesses, this 1st day of April, 50 1895.

ISIDOR SCHULZ.
